Patented May 18, 1920.

Walter Thorpe, ^{Inventor:}
by *Walter Thorpe*, ^{Atty's}

UNITED STATES PATENT OFFICE.

WALTER THORPE, OF MOUNT VERNON, NEW YORK, ASSIGNOR TO THE ELECTRIC PHONOGRAPH CORPORATION, OF NEW YORK, N. Y., A CORPORATION OF DELAWARE.

DESIGN FOR A PHONOGRAPH.

55,217.

Specification for Design.

Patented May 18, 1920.

Application filed March 18, 1920. Serial No. 366,998. Term of patent 14 years.

To all whom it may concern:

Be it known that I, WALTER THORPE, a citizen of the United States, residing at Mount Vernon, county of Westchester, and State of New York, have invented a new, original, and ornamental Design for a Phonograph, of which the following is a specification, reference being had to the accompanying drawing, forming a part thereof.

In said drawing:

The figure is a perspective view of an ornamental phonograph embodying the design of my invention.

I claim—

The ornamental design for a phonograph, substantially as shown.

WALTER THORPE.
